WHIP STOCK

Sherman G. Ackley, Bakersfield, Calif., assignor
to Peoples Finance and Thrift Company of
Bakersfield, Bakersfield, Calif., a corporation of
California.

Application December 18, 1937, Serial No. 180,603

5 Claims. (Cl. 255—1)

This invention relates to whipstocks. These devices are employed in a well hole to enable the drill bit to be deflected. This is necessary in drilling operations for different reasons; for example, to deflect a drill so as to avoid extremely hard formation that may be encountered in drilling the well, or a lost tool.

One of the objects of the invention is to provide a whipstock that can be carried down into the well on a drill, and which is maintained in a folded or unextended condition while passing down the well, but which, upon reaching the bottom of the well, will automatically move to an extended position, thereby presenting a guide in the path of the drill, which will deflect the drill from alignment with the axis of the hole.

A further object of the invention is to provide a whipstock of simple construction for this purpose, and having improved means for releasing it so as to enable its parts to occupy an extended relation to obstruct the lower end of the hole, and cause a deflection of the bit as it descends past the whipstock.

Further objects of the invention will appear hereinafter.

The invention consists in the novel parts and combination of parts to be described hereinafter, all of which contribute to produce an efficient whipstock.

A preferred embodiment of the invention is described in the following specification, while the broad scope of the invention is pointed out in the appended claims.

In the drawing:

Fig. 1 is a vertical section taken through a well hole and showing my whipstock in position after it has been expanded or extended, and is operated to deflect the bit. This view shows a portion of the whipstock shank in section.

Fig. 2 is a vertical section through the whipstock, and showing its parts in their unextended relation; that is to say, in the relation they have when the tool is being run down the well. The upper portion of this view illustrates the lower end of a drill bit in side elevation and partially in section.

Fig. 3 is a cross-section taken on the line 3—3 of Fig. 2.

Fig. 4 is a horizontal cross-section on the line 4—4 of Fig. 2.

Before proceeding to a more detailed description of the invention, it should be stated that in practicing the invention I provide a pair of members movably connected together and capable of being held in an unextended relation so that

they can be passed down a well. This is effected through the agency of some kind of latching means, which is constructed in such a way that when the whipstock arrives at the bottom of the well, the latching means will be released and enable the device to extend itself; that is to say, enable the two relatively movable parts to swing apart. One of the parts after being extended in this way, presents itself in an inclined position so that it is capable of operating to deflect the drill from the axis of the well. In the present instance, the whipstock is described as having frangible means for attaching the same to the side of the drill collar. This enables it to be passed down the well with the drill string, but as soon as the whipstock has been sprung, that is to say, extended at the bottom of the well, the continued downward movement of the drill will break the frangible means and permit the drill to engage the whipstock and be deflected by it.

In practicing the invention, and referring to Fig. 2 as illustrating a preferred embodiment of the invention, the whipstock has a body comprising two members 1 and 2, which are movably secured together to swing on a substantially horizontal axis, preferably by means of a hinge pin 3. These two members are provided with resilient means for urging them to an open or extended position, and in the present instance, this means comprises two leaf springs 4 and 5 attached respectively to the adjacent faces of the members 1 and 2, and pressing against each other.

In addition to this, I provide means for holding the parts 1 and 2 in a folded or unextended relation to enable the whipstock to be passed down the well. For this purpose I prefer to provide a latch 6 of inverted U-form having a relatively long stem 7 that is guided through one of the members so as to project downwardly below the lower end of the whipstock. When the lower end of this stem 7 strikes the bottom of the well, or an obstruction in the well, it pushes the latch upwardly and disconnects a short arm or pintle 8 from an opening 9 in which it is guided, said opening 9 passing through a lug 10 opposite to a similar lug 11 through which the stem 7 is guided. The release of the device in this way will enable the springs 4 and 5 to push the member 1 against the side 12 of the well hole 13 (see Fig. 1). As this member 1 performs this "kicking" or pushing function, it is not inapt to call this part a pusher member. When the lower end of the pusher member 1 forces itself against the wall 12, of course, the lower portion of the mem-

ber 2 will be pushed toward the opposite side of the well or hole.

The member 2 may be considered as a guiding member for the drill that is to be deflected, and in order to facilitate its performing this function, it is preferably provided on its outer side with a deflecting plate 14, the upper end of which is relatively deeply curved transversely so as to enable it to fit against the concave face of the other plate 15, which may be considered to form the body of the whipstock. This plate 15 has an upwardly extending concavo convex shank 16, the upper end of which is attached to a drill collar 17 by frangible means such as a frangible pin 15 or bolt 18. The lower end of the guide plate 14 is only slightly concave, as indicated.

The lower end of the guide plate 14 is preferably formed with an inwardly inclined extension or chisel or spur 19, which is intended to engage the hard formation at the bottom of the well so as to prevent the thrust of the drill from pushing the guide plate out of its way. This is important, for it is evident that the springs 4 and 5 would be wholly inadequate to hold the guide plate 14 from swinging inwardly under the action of the thrust of the drill. This chisel point 19 may be reinforced at each side by an integral flange 20.

When the drill head 21 carried by the drill collar, is forced downwardly by thrust in the tool string 22, the bolt 18 will be sheared and the drill will be deflected by the guide plate 14, as indicated in Fig. 1. This view, however, somewhat exaggerates the curvature in the drill string due to the deflection of the drill head.

Referring again to Fig. 2, it will be noted that in this figure the "kicker" or pusher member 1, is of substantially rectangular form in outline, as viewed from the rear, and the adjacent portion of the member 2 is cut away to form a substantially rectangular socket or gap 23 to receive it. When the whipstock is passing down the well, the shank 16 is substantially in line with the back of the pusher member 1, as indicated in Fig. 2, but after the release of the whipstock occurs, the joint formed by the hinge pin 3 will, of course, spring forwardly; that is, toward the axis of the well, so that the parts will have substantially the relation indicated in Fig. 1.

It is understood that the embodiment of the invention described herein is only one of the many embodiments this invention may take, and I do not wish to be limited in the practice of the invention, nor in the claims, to the particular embodiment set forth.

What I claim is:

1. In a whipstock for deflecting a drilling tool in a well to change the direction of the well bore, the combination of a guide member and a pusher member pivotally attached thereto, one of said members having an extension at its upper end for attachment to the side of a drill collar on a drill string, said extension lying adjacent the side of the well bore so as to leave the well bore unobstructed for the passage of a drilling tool, resilient means urging the said members apart and toward an extended relation at their lower ends, and a latch for latching said members in an unextended relation while passing down the well, said latch having means for engaging the well bottom or an obstruction in the well bore to release the same, to enable the pusher member to engage one side of the well bore and cooperate with the resilient means to force the lower end of the other member laterally in the well.

2. In a whipstock for deflecting a drilling tool in a well, the combination of a body comprising a pair of members pivotally connected, resilient means for urging the said members to swing apart into an extended position enabling one of said members to operate as a deflecting member to assume an inclined position for deflecting a well tool, and latching means for holding said members together in an unextended position, said latching means having means for releasing the same by contact with the well bottom or an obstruction in the well bore, said deflecting member having means at its lower end to bite into the well bottom and prevent the thrust of the drill while being deflected, from pushing the deflecting member aside.

3. In a whipstock for deflecting a drilling tool in a well, the combination of a guide member and a pusher member pivotally attached thereto, one of said members having an extension at its upper end for attachment to a drill collar on a drill string, resilient means urging the said members apart and toward an extended relation at their lower ends, and a latch for latching said members in an unextended relation while passing down the well, said latch having means for engaging the well bottom or an obstruction in the well bore to release the same, to enable the pusher member to engage one side of the well bore and cooperate with the resilient means to force the lower end of the other member laterally in the well, to assume an inclined position extending across the well bore, said guide member having a spur below operating to bite into the well bottom and prevent the thrust of the drill from pushing the guide member to one side.

4. In a whipstock for deflecting a drilling tool in a well, the combination of a body member having an upwardly extending shank of concavo-convex form in substantially horizontal section adapting the same for attachment to the side of a drill collar, said shank located adjacent the side of the well bore, said body member having an inclined guide extension to be engaged by the drill and deflected, a pusher member pivotally attached to the body member and extending downwardly substantially in alignment with the shank, resilient means between the guide extension and the pusher member urging the pusher member toward the wall of the well, and urging the guide member to assume an inclined position across the well bore, and a latch for latching the pusher member in its unextended position, said latch having an extension projecting below the lower end of the pusher member and operating when it strikes the bottom of the well or an obstruction in the bore, to disengage the latch.

5. In a whipstock for deflecting a drilling tool in a well, the combination of a body composed of a pair of members pivotally connected to each other, resilient means for urging the said members to swing apart into an extended position, one of said members to operate as a deflecting member and being made to assume an inclined position extending across the well bore for deflecting a well tool, and latching means for holding said members together in an unextended position, said latching means having means for releasing the same by contact with the well bottom or an obstruction in the well bore, said deflecting member having means at its lower end to bite into the well bottom and prevent the thrust of the drill while being deflected, from pushing the deflecting member aside.

SHERMAN G. ACKLEY.
